Specification for Design.

Patented Oct. 8, 1912.

Application filed August 23, 1911. Serial No. 645,664. Term of patent 7 years.

To all whom it may concern:

Be it known that I, LINDSLEY SCHEPMOES, a citizen of the United States, residing at Hasbrouck Heights, county of Bergen, and State of New Jersey, have invented a new, original, and ornamental Design for Pendant-Fixtures, of which the following is a specification.

The nature of my design is fully illustrated in the accompanying drawing, to which reference is made, and in which—

Figure 1 represents an elevation of the design, and Fig. 2 a top plan view thereof.

My design comprises an inverted cup-like pendant structure, the periphery of

which flares generally outwardly in opposite directions from an intermediate portion, the lower portion being of greater transverse extent than the upper portion and extending laterally relatively abruptly therefrom, having the contour and relative proportion of parts shown.

I claim:

The ornamental design for a pendant fixture as shown and disclosed.
